UNITED STATES PATENT OFFICE.

GEORGE J. FRIEND, OF KINGSLEY, OREGON.

BOLSTER ATTACHMENT.

SPECIFICATION forming part of Letters Patent No. 748,600, dated January 5, 1904.

Application filed October 22, 1903. Serial No. 178,126. (No model.)

To all whom it may concern:

Be it known that I, GEORGE J. FRIEND, a citizen of the United States, residing at Kingsley, in the county of Wasco and State of Oregon, have invented certain new and useful Improvements in Bolster Attachments, of which the following is a specification.

As is well known, it is customary for drivers of vehicles to sit upon one side of the seat carried by the body of the vehicle, and, in loaded vehicles more especially, the above causes the body of the vehicle to tilt in the direction or toward the side upon which the driver is seated. The tilting of the wagon-body tends to strain the king-bolt so as to cause binding thereof and, further, causes uneven wearing upon the bottom of the wagon-body.

It is the object of this invention to provide an attachment to be applied to the bolster of the wagon-body for coöperation with adjacent devices carried by the axle to limit the movement of the wagon-body in such a manner as to prevent the tilting action above described caused by the weight of the driver at one side thereof.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view showing the application of the attachment. Fig. 2 is a front elevation of a wagon-body, the attaching device being shown in relative working position. Fig. 3 is a detail perspective view of the engaging arm carried by the bolster. Fig. 4 is a vertical sectional view through the attaching device and adjacent parts to which the same are secured.

Corresponding and like parts are referred to in the following description and indicated in all the views of the drawings by the same reference characters.

The invention is shown in connection with an ordinary construction of load-vehicle and

consists of the arm 1, which is secured to the under side of the bolster 2 of the wagon-body 3. The arm 1 is secured at its inner end to the bolster by means of a fastening-bolt or analogous device which connects bifurcated end portions 1^a and 1^b, which embrace the sides of the bolster, as clearly shown. The outer end of the arm 1 is provided with the pendent bracket 4, to which is secured a friction-roller 5, which is mounted upon an axle extending laterally from the bracket and secured thereto in any substantial manner. The arm 1 extends beyond the bracket and is provided with pendent flanges 6, which are received by a hanger 7, secured to the end of the bolster 2. The hanger 7 is of approximately U form and supports a spring 8 between the arms thereof, which spring is interposed between the flanged end of the arm 1. Seats 9, consisting of cup-shaped disks, are disposed at opposite ends of the spring. The hanger 7 is secured to the bolster 2 by means of a cross-bolt passing through the upper portions of the arms of the hanger and through the bolster. The vertically-disposed bolt 10 passes through an opening in the lower portion of the hanger through openings in the seats 9, entering a recess in the under side of the bolster. A nut 11 is disposed between the upper disk-seat 9 and the end of the arm 1 between the arms of the hanger, and this nut permits adjustment of the tension of the spring 8 for purposes which will appear hereinafter. The axle 12 carries an engaging bar 13, which bar 13 is of approximately arcuate form, having attaching end portions 14 extending therefrom, the latter being secured to adjacent parts of the axle structure. The bar 13 is used in the capacity of a stop means to be engaged by the roller 5, which is disposed beneath the said bar. The engaging relation of the roller and the engaging bar 13 prevents sagging or tilting of the wagon-body to one side, due to the weight of the driver who sits thereon. The engaging bar 13 is reinforced about centrally thereof by a stop 15, which projects upwardly from the cross-bar 16 of the axle 12. The strain upon the engaging bar is greatest at the central part, because of the fact that the axle is normally in a position to cause the roller to remain in contact with this portion of the said bar, and for

this reason it is desirable that the reinforced means 15 be utilized to support the bar 13 in the manner stated. As the vehicle advances, the roller 5, engaging beneath the engaging 5 bar 13, prevents any sagging or tilting of the side of the body of the vehicle carrying the weight of the driver, the spring 8 being ad- justed to compensate for the weight aforesaid, as well as to permit movement of the 10 wagon-body as the vehicle passes over ob- structions causing vibration or jar. When different drivers are employed upon the ve- hicle, the tension of the spring 8 is adjusted in accordance with the weight of the driver 15 in a manner which will be readily com- prehended, the greater the weight of the driver the greater the tension of the spring, and vice versa. The friction - roller 5 serves in the capacity of a stop, and the frictional contact 20 thereof is reduced to a minimum in the turning movement of the vehicle.

The parts comprising the invention are preferably made of metal, such as steel cast- 25 ings or pressed-steel parts, this depending greatly upon the size of the attachment and the vehicle to which it is to be applied.

Having thus described the invention, what is claimed as new is—

1. In an attachment for vehicles, the com- 30 bination with an engaging arm secured to a bolster of the vehicle, an engaging bar se- cured to the axle, interlocking means between the engaging bar and the engaging arm, and spring means coöperating with the engaging 35 arm.

2. In an attachment for vehicles, the com- bination with an engaging arm secured to a 40 bolster of the vehicle, an arcuate engaging

bar carried by the axle of the vehicle, and a friction-roller carried by the engaging arm 45 aforesaid and engaging beneath the engaging bar and forming a stop to limit the movement of the vehicle-body.

3. In a vehicle, the combination with an engaging arm carried by a bolster thereof, a 50 hanger secured to the bolster and receiving the engaging arm, an engaging bar carried by an axle adjacent the arm extending from the bolster, spring means supported by the hanger for coöperation with the engaging arm of the 55 bolster, and stop means extending from the said arm for coöperation with the engaging bar.

4. In an attachment for vehicles, the com- bination with an engaging arm secured to a 60 bolster of the vehicle, an arcuate engaging bar secured to the axle of the vehicle, a hanger pendent from the bolster and receiving the outer end of the engaging arm, and a roller carried by the engaging arm and engaging 65 beneath the engaging bar.

5. In an attachment for vehicles, the com- bination with an engaging arm secured to a 70 bolster of the vehicle, an engaging bar car- ried by an axle of the vehicle, stop means projected from the engaging arm for coöper- 75 ation with the engaging bar, and attachable tension means coöperating with the engaging arm.

In testimony whereof I affix my signature 80 in presence of two witnesses.

GEORGE J. FRIEND. [L. S.]
